UNITED STATES PATENT OFFICE.

WILLIAM STANLEY, OF GREAT BARRINGTON, MASSACHUSETTS, ASSIGNOR
TO THE STANLEY INSTRUMENT COMPANY, OF MASSACHUSETTS.

METHOD OF PRODUCING PHASE DISPLACEMENT.

SPECIFICATION forming part of Letters Patent No. 658,815, dated October 2, 1900.

Application filed May 2, 1900. Serial No. 15,165. (No specimens.)

To all whom it may concern:

Be it known that I, WILLIAM STANLEY, a citizen of the United States, residing at Great Barrington, Berkshire county, Massachusetts, 5 have invented certain new and useful Improvements in Methods of Producing Alternating Magnetic Flux Displaced in Phase from the Impressed Electromotive Force, of which the following is a full, clear, and exact 10 description.

My invention relates to improvements in methods of producing alternating magnetic fluxes displaced in phase from the phase of the electromotive force of the energizing-current; and it consists in producing certain magnetic actions and reactions so related as to produce that result, and has for its object to provide a simple, convenient, and reliable method of obtaining this end.

20 The following is a description of my invention, together with the apparatus with which it may be practiced, reference being had to the accompanying drawings, in which—

Figure 1 represents a side elevation of suitable apparatus. Fig. 2 shows a plan view of the same. Fig. 3 is a diagram illustrating the various forces and their resultants. Figs. 4, 5, and 6 show other forms of apparatus with which the invention may be practiced.

30 In carrying out the invention I employ an iron or soft-steel core A, laminated to prevent eddy-currents in the usual manner, which core nearly embraces the energizing-coil B, as shown in Fig. 1, in which a principal magnetic circuit follows the line 1 2 5 6, while a subsidiary magnetic circuit follows the line 1 2 3 4 5 6. The magnetic circuit is opened at C and D, and the flux is caused to pass across air-gaps at these points, each of which 35 is of such dimensions that the paths 1 2 5 6 and 1 2 3 4 5 6 have a constant coefficient of induction and are of low magnetic reluctance.

From this construction it is evident that the value of the flux found in the gaps C and 45 D will be inversely as the reluctances of these gaps, so that by adjusting the reluctance of either the value of the flux in the one or the other may be adjusted with great exactness and that the inductance of the system, and 50 consequently the time constant of the apparatus, can be made very great by making the

value of either air-gap reluctance comparatively low. The gap C is therefore made so small as to make the time constant very great, but not so narrow as to prevent an appreciable flux passing across the gap D. Such an arrangement of itself, however, is unable to give a lag to the current or magnetization of the apparatus of more than about eighty to eighty-two or eighty-three degrees when energized by currents of the usual frequency employed in the arts.

Now I have discovered that by inserting an electrically-closed-circuited system—such, for instance, as a disk E, of conducting material—in the air-gap D, I can act upon the magnetic flux passing through said gap so as to cause the effective flux to no longer coincide with the phase of that passing through the gap C or the phase of the current in the coil B, but to be delayed by the magnetizing effect of the eddy-currents induced in the disk E, and, further, I have discovered that the phase angle of the effective or resultant flux of the gap D depends upon the conductivity of the inserted closed-circuited system. In constructing apparatus to carry out my invention, therefore, so as to obtain, for instance, ninety degrees displacement, having made an electromagnetic system having an air-gap of such reluctance that the current in the energizing-coil is retarded in the neighborhood of eighty degrees behind the impressed electromotive force by the self-induction of the energizing-coil, I insert within the gap in said system a closed-circuited conducting system of such conductivity that the currents induced therein shall set up a magnetomotive force, which acting with the magnetomotive force due to the current in the energizing-coil shall produce a resultant effective flux displaced from the phase of the current in the energizing-coil by the complement of its angle of lag.

These forces and their resultants are diagrammatically illustrated in Fig. 3, in which $h\ i$ represents the electromotive force of the system, and $i\ j$ the phase angle of the current in the coil B and the phase angle and strength of the magnetomotive force across the gap D due to the coil B. $i\ k$ represents both the phase angle and strength of the magnetomotive force due to the eddy-currents in the disk

E, and il represents the resultant of the magnetomotive forces ij and ik , which resultant is displaced in phase from the original magnetomotive force ij by the angle jil , which 5 is the complement of jh , the angle of lag of the current in the coil B making the angle of the resultant or effective flux ninety degrees from the electromotive force of the system.

10 It is to be noted that the magnetism threading the coil B is not appreciably affected by the presence of the disk E, the reactive effect of the current induced in the disk being substantially confined to the magnetic circuit 2 15 3 4 5.

It will be seen that the principles which I employ in the above-described apparatus to effect the desired result are a magnetic circuit of very high inductance having a definite air-gap, and consequently a fixed and definite time constant independent of any reactive effects occurring by reason of the use of the flux used in the apparatus, and a second path for a part of the flux having a definite air-gap, and consequently a definite time constant, in which is located a conductive circuit for the purpose of modifying the time of the flux in the path which it embraces, to the end that the common flux passing through 25 the coil D may pass through two branches, one of which will be delayed in phase behind the other by the angle which, added to the angle of current lag in the energizing-coil, makes the desired displacement.

30 Fig. 4 represents another means for carrying out the invention, in which B is the energizing-coil upon a central projection F, there being two air-gaps H and D, in one of which is placed the conducting-disk E, the other preferably containing a non-magnetic material, the volume of flux across the gap D depending on the relative width of the gap H. When the coil B is energized, the flux passes in part through the circuit 7 8 9 10 and 45 in part through the circuit 7 10 11 12, while the magnetism due to the induced currents in the disk E is confined to the magnetic circuit 7 8 9 10 11 12, producing in the gap D a resultant effective flux of ninety degrees 50 placement when constructed with proper proportions in substantially the same manner as in the apparatus of Figs. 1 and 2.

In Fig. 5 there are two energizing-coils B' B^2 and five gaps $D' I' I^2 J' J^2$, the flux from 55 the coils $B' B^2$ passing in part through the entire circuit and in part through their local circuits, while the reacting magnetizing effect of currents in the disk E is confined to the circuit 13 14 15 16.

60 In the construction shown in Fig. 6 there are four energizing-coils $B' B^2 B^3 B^4$ arranged in series and wound upon U-shaped magnets, so as to produce poles of alternately-different polarity, the magnets being arranged so as to form two air-gaps $D' D^2$, in which is placed the disk E. Each of the U-shaped magnets has two magnetic paths through local circuits

20 17 18 19 and 24 21 22 23, respectively, and also a common circuit through 17 18 19 20 21 22 23 24, the local circuits being formed by 70 the parts $K' K^2$, which are separated from the main path of the magnets by gaps m , filled with non-magnetic matter. The flux across the gaps $D' D^2$ depends on the width of the gaps m . In this case the reaction of the eddy-currents in the disk E is expended in the local circuit 17 20 21 24, and in this way but little 75 affects the energizing-coils.

The ninety degrees displacement of the magnetic flux relatively to the electromotive force 80 of the system is in these last two constructions also obtained by making the disks of such conductivity that the magnetomotive forces due to their eddy-currents will be of such phase and strength that, acting with the 85 magnetomotive forces due to the energizing-coils, they will produce resultants differing in phase from the magnetomotive forces of said coils by the complement of the angle of lag of the current in the energizing-circuit. 90

What I claim is—

1. The method of producing a flux of definite angular displacement from the electromotive force impressed upon a circuit which consists in producing a flux of lesser angular 95 displacement than that required by means of a current in a simple coil of high inductance and fixed time constant and by such flux inducing secondary currents within a closed conductor differing in phase from said energizing-currents and so located that the time of flow of such secondary currents cannot change the time constant of the energizing coil or coils and thereby producing a resultant flux having the desired angular displacement, substantially as described. 100

2. The method of producing a flux displaced by a definite amount relatively to the phase of the impressed electromotive force which consists in producing by a coil traversed by current due to said impressed electromotive force, a primary magnetomotive force of lesser angular displacement than that required, and by the flux due to said primary magnetomotive force inducing secondary currents within a closed circuit, setting up a secondary magnetomotive force by said secondary circuits and thereby a flux in a definite path coinciding in part that of the flux due to said primary magnetomotive 110 force, but not passing through said energizing-coil, and combining said primary and secondary magnetomotive forces at a common portion of their paths and so as to produce a resultant magnetomotive force and consequent flux having the desired phase displacement, substantially as described. 115

3. The method of producing an alternating magnetic flux displaced by ninety degrees from the electromotive force of the system 120 which consists in energizing by an alternating current an open magnetic circuit of high inductance and thereby producing magnetomotive forces greatly lagging behind the elec- 125

tromotive force of the system and producing thereby a divided flux, inducing by one division of said flux alternating currents, said inducted alternating currents setting up 5 magnetomotive forces such that when combined with said division of the magnetomotive forces due to the energizing-coil shall produce in said gap as a resultant an alternating magnetomotive force and flux dis- 10 placed from the electromotive force of the system by ninety degrees, and combining said magnetomotive forces, substantially as described.

4. The method of producing a magnetic flux 15 having a phase difference of ninety degrees relatively to the electromotive force of the system, which consists in producing an energizing-current displaced in phase by an angle of near eighty degrees and thereby setting up in a magnetic circuit of high induct- 20 ance a magnetomotive force displaced from said electromotive force by a correspond-

ing angle and inducing in a closed-circuited system by the flux due to said magnetomotive force alternating currents displaced in phase 25 therefrom, and producing by said induced currents a magnetomotive force of proper strength and phase not affecting the time-constant of the circuit carrying the energizing-current and combining said magnetomotive force with the magnetomotive force due to the energizing-coil so as to produce a resultant or effective flux differing in phase from the magnetizing-current by the complement of its own angle of lag, and from the 30 electromotive force of the system by ninety degrees, substantially as described.

Signed at Great Barrington, Massachusetts, this 28th day of April, 1900.

WILLIAM STANLEY.
